(57) **CLAIM**

The ornamental design for a media container as shown and described.

DESCRIPTION

FIG. 1 is a top perspective view of a media container showing our new design.

FIG. 2 is a front view of the media container of FIG. 1.

FIG. 3 is a back view of the media container of FIG. 1.

FIG. 4 is a right side view of the media container of FIG. 1.

FIG. 5 is a left side view of the media container of FIG. 1.

FIG. 6 is a top view of the media container of FIG. 1.

FIG. 7 is a bottom view of the media container of FIG. 1; and,

FIG. 8 is an exploded top perspective view of the media container of FIG. 1.

The dashed lines depict portions of the media container that form no part of the claimed design.

The dot-dash dot broken lines depict the boundaries of the claim and form no part thereof.
